August Kuring,
by Robert Burns
Attest,

UNITED STATES PATENT OFFICE.

JOHN V. LARSON AND AUGUST KURING, OF CHICAGO, ILLINOIS; SAID AUGUST KURING ASSIGNOR TO SAID JOHN V. LARSON.

AUTOMATIC NUT WRENCH.

Application filed August 30, 1924, Serial No. 735,215. Renewed March 16, 1926.

This invention relates to that type of nut wrenches in which the operating handle of the wrench is pivotally connected to the stationary wrench jaw and provided with a guideway for the sliding companion movable wrench jaw, with said movable jaw forcibly held to an engagement with a nut by a gearing of similar connection between said movable jaw and the pivoted handle, with said movable jaw having a tendency under the influence of a spring to move towards the companion stationary wrench jaw.

10 The object of the present improvement is to provide a structural formation and arrangement of parts whereby the interposed spring, such as above referred to, is securely housed within the body of the wrench and effectively protected from accidental injury.

20 Another object is to provide a movable abutment on the handle member of the wrench for the aforesaid spring, whereby the tension of the spring can be readily released from its active jaw closing tendency and placed in an inactive position, whereby

25 the movable jaw member of the wrench is left free for manual adjustment by the fingers of the user, all as will hereinafter more fully appear.

30 In the accompanying drawing:—

Fig. 1 is a side elevation of a nut wrench having the present improvement applied.

Fig. 2 is a sectional view on line 2—2, Fig. 3.

Fig. 3 is a longitudinal section on line 3—3, Fig. 2.

Fig. 4 is a perspective view of the spring and associated wrench parts in a separated condition.

Like reference numerals indicate like parts in the several views.

The type of wrench structure shown in the drawing as illustrating the application of the present improvement, is substantially the same as set forth in our prior application for patent, Serial No. 669,049, filed Oct. 17, 1923.

The relatively stationary body portion 1 of the wrench is formed with the usual outstanding nut engaging jaw 2 at one end, and with a pair of oppositely extending cheek plates 3 in separated relation to each other to provide a receiving cavity in which the operating handle 4 is journaled by a pivot pin 5 as shown. The cheek plates 3 in connection with the usual longitudinal channel

in the body portion 1, provides a slideway for the rectilinear movement of the movable wrench jaw 6 to and from the stationary jaw 2 aforesaid. In the construction shown said jaw 6 constitutes an outstanding portion of a head or block 7 moving in the aforesaid slideway, and having its back formed with a toothed rack or gear 8.

The pivot hub 9 of the operating handle 4 has a portion of its periphery formed with gear teeth 10, having operative engagement with corresponding gear teeth 8 of the movable wrench member aforesaid.

The plurality of gear teeth 10 are preferably formed on the handle hub 9 with their pitch lines or centers at progressively increasing distances from the axis of rotation of the hub, with each of such distances slightly less than the distances across the side faces of each respective nut of the range 75 of nut sizes the wrench is designed to manipulate, and in connection with such progressive increase in the radial pitch lines of the plurality of teeth 10, the formation of such teeth of correspondingly increased sizes 80 so as to provide the requisite strength to resist the increased stress to which they are exposed by the increased size of the nuts they are required to manipulate.

The series of gear teeth 11 of the rack bar 8 of the movable jaw member, have a complementary formation to that of the plurality of gear teeth 9 of the wrench handle 4, both in relation to pitch lines and increased sizes of teeth, as shown.

90 The movable wrench jaw 6 in the present type of wrenches, has a yielding tendency towards the stationary wrench jaw 2 by means of a spring connection intermediate of the two jaws, with the spring connection acting to 95 maintain the wrench jaw in a normally closed condition, as well as to return the jaws to contact with the sides of the nut operated on, when the wrench is operated for speed with an opening movement of the 100 jaws in the reverse stroke or turn of the operating handle 4. And in this connection the material part of the present improvement involves a structural formation of a spring of the type above described and the 105 associated wrench parts as follows.

In one of the cheek plates 3 above described, an annular containing cavity 12 is formed in concentric relation to the pivot pin 5, and separated from the receiving ori- 110

fice of said pin by an annular wall 13 as said arm to hold the spring in active operation.

Within the cavity 12 is arranged a coiled spring 14 of the scroll type shown, the inner end of which has a lateral prong or extension 15 for engagement in a holding orifice formed therefor in the bottom of said cavity. The outer end of the spring 14 is formed with a lateral extension or hook 16 having fixed attachment to the adjustable abutment plate or arm now to be described.

The abutment plate or arm has a main portion 17 of a centrally orificed disk form encircling the shank of the pivot pin 5 and having a diameter sufficient to cover the cavity 12, to enclose and protect the spring 14. Extending from one side of said body portion 17, is an arm 18 projecting beyond the cheek plate 3 and having at its outer and free end a lateral flange 19, formed with a notch or recess 20, for the purpose hereinafter set forth.

In adjacent relation to the outer end of the arm 18 a transverse orifice is formed in the wrench handle 4 and in said orifice is arranged a sliding stop pin 21, headed at both ends and capable of limited transverse movement in said orifice. As so arranged, and with a headed end of the stop pin 21 pushed into the path of the arm 18, the same is adopted to have holding engagement with the stop pin, through an engagement of the notch 20 with the head of said stop pin. As so engaged, the tensional stress of the spring 14 acts intermediate of the wrench handle 4 and wrench body 1, to yieldingly force the jaw members together. With a disengagement between the arm 18 and the stop pin 21, said arm moves against the edge of the cheek plate 3, to a dormant condition, leaving the wrench jaws free to be moved to and from each other by the fingers of the user.

Having thus fully described our invention, what we claim and desire to secure by Letters Patent is:—

1. In a wrench of the type described, a pair of jaw members, one movable to and from the other, an operating handle pivoted to one jaw member and operatively connected to the other jaw member, a spring encircling the pivot axis of the handle member with one end fixedly engaging the jaw member to which said handle is pivoted, a swinging arm associated with said pivot axis and having fixed engagement with the other end of the aforesaid spring, and a movable stop member adapted for engagement with

2. In a wrench of the type described, a pair of jaw members, one movable to and from the other, an operating handle pivoted to one jaw member and operatively connected to the other jaw member, a spring encircling the pivot axis of the handle member with one end fixedly engaging the jaw member to which said handle is pivoted, a swinging arm associated with said pivot axis and having fixed engagement with the other end of the aforesaid spring, and a headed stop pin having limited lateral sliding movement in the wrench handle and into and out of the path of said swinging arm.

3. In a wrench of the type described, a pair of jaw members, one movable to and from the other, an operating handle pivoted to one jaw member and operatively connected to the other jaw member, a spring encircling the pivot axis of the handle member with one end fixedly engaging the jaw member to which said handle is pivoted, the jaw member having an annular containing cavity for said spring, a swinging arm associated with said pivot axis and having fixed engagement with the other end of said spring, said arm having a circular hub portion forming a closure for the cavity aforesaid, and a movable stop member adapted for engagement with said arm to hold the spring in active operation.

4. In a wrench of the type described, a pair of jaw members, one movable to and from the other, an operating handle pivoted to one jaw member and operatively connected to the other jaw member, a spring encircling the pivot axis of the handle member with one end fixedly engaging the jaw member to which said handle is pivoted, the jaw member having an annular containing cavity for said spring, a swinging arm associated with said pivot axis and having fixed engagement with the other end of said spring, said arm having a circular hub portion forming a closure for the aforesaid cavity and with a flange on its free end formed with a holding notch, and a headed stop pin having limited lateral sliding movement in the wrench handle and into and out of the path of said swinging arm.

Signed at Chicago, Illinois, this 27th day of August, 1924.

JOHN V. LARSON.
AUGUST KURING.
